Des. 208,578
Patented Sept. 12, 1967

208,578

COAXIAL LINE METER

Philip F. Puljer, Parma, Ohio, assignor to Bird Electronic Corporation, Solon, Ohio, a corporation of Ohio

Filed Nov. 18, 1966, Ser. No. 4,735

Term of patent 14 years

(Cl. D52—6)

Fig. 1

Fig. 2

Fig. 4

Fig. 3

Fig. 5

FIGURE 1 is a plan view of a coaxial line meter illustrating my new design;

FIGURE 2 is a side elevational view of the coaxial line meter;

FIGURE 3 is a front elevational view of the coaxial line meter;

FIGURE 4 is a rear elevational view of the coaxial line meter; and

FIGURE 5 is a top perspective view of the meter with the broken line portion omitted.

The undisclosed side of the meter is substantially the same in appearance as the side shown in FIG. 2.

The essential features of the design are shown in the full line portions of the drawing.

I claim:

The ornamental design for a coaxial line meter, substantially as shown and described.
